TURBINE WHEEL

David P. Eastman, Chicago, Ill., assignor to
United Specialties Company, Chicago, Ill., a
corporation of Delaware

Application September 16, 1946, Serial No. 697,361

9 Claims. (Cl. 253—77)

1

This invention relates to a turbine wheel and has for one object to secure a plurality of buckets onto the wheel.

Another object is to secure the buckets on a turbine wheel without actually fastening the buckets by welding, braising or otherwise to the wheel.

Another object is to provide a turbine wheel with parts which, under the influence of centrifugal force, tend to clamp the buckets tightly to the wheel.

Another object is to provide a multi-part turbine wheel with a plurality of buckets, the parts being so arranged that the load of the buckets is distributed between the several parts.

Another object is to produce a turbine wheel suitable for holding buckets made from flat stock.

Other objects will appear from time to time throughout the specification and claims.

This invention is illustrated more or less diagrammatically in the accompanying drawings, wherein:

Figure 1 is a section through that portion of the wheel in which the buckets are positioned;

Figure 2 is a side elevation of a bucket;

Figure 3 is a transverse section taken at line 3—3 of Figure 2;

Figure 4 is a plan view of one form of turbine wheel;

Figure 5 is a section illustrating the form of Figure 1 on an enlarged scale and in a modified position, after use; and

Figures 6 and 7 are diagrams illustrating the factors which control the design of the bucket holding parts.

Like parts are indicated by like characters throughout the specification and the drawings.

The turbine wheel itself is formed of a main member 1 which may be a disc and is preferably reduced, as at 2, and enlarged, as at 3, to form a peripheral bead or enlargement. The under or inner surfaces of the member 3 are inclined, as at 4. Buckets 5 are provided with tongues or extensions 6 which, when the buckets are in position, embrace the bead 3 and are in contact with the inclined surfaces 4. The ends of the members 6 are laterally extended as at 7.

Positioned on either side of the member 1 and secured to it by rivets 8, or otherwise, are plates 9, 9. Each plate is provided with an inwardly directed portion 10, having a depression 11. The members 6 and 7 lie flush against the inner faces of the inwardly bent portions 10. The shape of the bead 3 and the portions 10 is such that the

2

clearance between them is equal to the thickness of the portions 6, 7.

In the clearance provided between the reduced portions 2 of the member 1 and the plates 9 there are positioned two annular members 12. As shown, some clearance 13 is provided between these members 12 and the shoulder formed by the reduced portion 2. The members 12 are provided with outward extensions 14 and cut away portions 10 or clearances 15. The clearances 15 hold the members 12 out of contact with the major part of the bucket portions 7. The extensions or enlargements 14 are in contact with the members 7 only at their outer ends and assist in holding 15 them in contact with the inner faces 11 of the members 10.

The modified showing of Figure 5 differs from that of Figure 1 only by the change in shape of the portions 7 due to action of the outer plate 20 members. As the wheel is rotated, centrifugal action causes the members 12 to move, creep or enlarge, and thus forces the ends of the parts 7 into the depressions 11.

The diagrams of Figures 6 and 7 illustrate on 25 an enlarged scale the action which takes place when the members 6, 7 of the buckets are affected by centrifugal force. These diagrams also illustrate the conditions which determine the particular design and angular relationship or shape 30 of the members 10 and the bead 3 and its inclined surface 4.

For the purposes of this discussion, the members 6, 7 may be considered as comprising flexible bands. They are anchored at A through the 35 pressure of the weights 12 which press them into the depressions 11 or otherwise hold them. The weights 12 press against the portions 7 of the members 6 whether the depressions 11 and the reduced portions 14 be provided or not. In other 40 words, if the surface of the members 12 were smooth and if the inner surface of the members 10 were smooth the weights 12 would still press against the members 7 and hold them against the inner surfaces of the members 10.

45 The load of the bucket 5 imposes tension, indicated by the letter T_1 at the top of Figures 6 and 7. Neglecting, for the purposes of this calculation, the effect of friction around the bends, there will be an equal and opposite tension T_2 at 50 another point B beyond the first bend. The reaction of these two tensions gives rise to a crowding of the members 6 against and around the bend on the bead 3 and pressure is thus exerted against the band in the region of this radius as indicated 55 by the arrows P in Figures 6 and 7. The resultant

of all these pressures can be expressed by line R which acts at angle θ of such a value that R is on the bisector of the angle described by T₁ and T₂. The resultant R has a vertical component L which is a measure of the amount of pull of the bucket taken by the bead 3.

Figures 6 and 7 differ only in the degree of angular separation of T₁ and T₂. It is obvious that as the angle between T₁ and T₂ is decreased as in Figure 7, the angle θ is increased and the length of R is also increased as may be shown by a full vector diagram of forces, and L increases both as a result of the increase in magnitude of R, and due to the geometry of the force-triangle here shown.

Load L would be equal to T₁ if T₁ and T₂ were 90° apart. Load L would be zero if T₁ and T₂ were 180° apart. If load L is less than T₁, the difference between L and T₁ is carried by the disc 9. Thus by changing the angular displacement of the surface 4 of the bead 3; and, consequently, the angular displacement of T₂, the bucket load may be shifted from the bead 3 to the disc 9 through the flange 10.

The counterweight 12 may be cut away as at 15 to insure pressure close to the base of the flange 10 whether or not the flange 10 is provided with the depression 11. It is preferable, although not essential, to cause this pressure of the weight 12 to be exerted close to the base of the flange 10, because the flange 10 is in a sense a weakness. The flange 10 is subject to bending with resulting non-uniform stress of the disc 9. Concentrating the loads of the weights 12 at the base of the flange 10 imposes the least bending effect upon this flange.

Clearances are shown at several places. A slight clearance is provided about the rivets 8 so that the rings 12 are not held by the rivets against some outward movement. Also a clearance is provided between the plates 1 and 9. When the plates are fastened together, this clearance may be greatly reduced or may disappear. The purpose of the clearance is to prevent jamming of the parts in assembly and to make certain that the parts 10 are pressing against the member 2 and the bead 3. If no such clearance were provided, the parts 1 and 9 might come in contact prematurely when the wheel is assembled and might thus prevent adequate holding action of the parts 10 on the bucket members 6, 7.

The clearances referred to are minute and usually amount to a very few thousandths of an inch, but their presence is important and desirable.

The cut away portions or depressions 11 and 15 might be omitted; if they were, the members 12 would have full contact with the portions 7, and the portions 7 would be pressed across their lengths in contact with the members 10. The provision of the cut away portions or depressions 11 and 15 is desirable, but the invention is not limited to this feature.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of this invention are as follows:

The wheel of this invention is assembled by forming the central member 1 of the several parts. The buckets are positioned over the bead or enlargement 3 and the portions 6 of the bucket 5 are shaped to fit closely against the bead and against the sides of the reduced portion 2 and their ends are bent outwardly. The ring-like members 12 are put in place with their enlargements or extensions 14 bearing against the area near the ends of the members 1. The outer parts 9 are put in place in the positions shown and a suitable number of rivets is tightened in perforations formed in the parts and the wheel is thus held together.

Under the influence of centrifugal force the buckets tend to be distorted, broken or thrown off the wheel. The shape of the wheel parts which engage and contact the bucket members 6, 7 is such as to resist any displacement of or damage 20 to the buckets as a result of centrifugal force.

The portions 10 are in effect unbalanced or unsymmetrical, each with respect to its member 9. Under the influence of centrifugal force these portions therefore tend not merely to move outwardly, but to rotate with respect to the portions 9 and they thus exert an additional pressure which tends to hold the portions 6 of the bucket tightly against the bead 3. The parts 10 are also supported by the bead or part 3. The bead 3 thus strengthens the parts 10 by supporting them and by limiting their outward movement. The bead also takes a part of the bucket load since the parts 6, 7 are in part wrapped around its corner. The members 12 also tend to be thrown or expanded outwardly under the influence of centrifugal force, and this causes them, through their portions 14, to exert an added pressure upon the ends 7 of the members 6 and thus to force them into ever tighter engagement with the inner surfaces 11 of the members 10.

The construction of the wheel which has just been described is such that two means are provided for utilizing centrifugal force to grip and hold the buckets in place. The greater the speed 45 of the wheel the greater is this force, and thus the tendency of the buckets to leave the wheel under the influence of centrifugal force is resisted in response to centrifugal force by a relatively slight movement or deformation of the wheel or parts of the wheel. Since the wheel parts are fastened together, the movements just described are necessarily slight. Some distortion, displacement or "grow" will, however, occur and experience has shown that it does occur. The 50 wheel of the present invention has been designed to take advantage of this movement or growth which would otherwise be a disadvantage and to utilize it in clamping and holding the buckets in place.

For some purposes and where the wheel is not to be run at great speed, the members 12 might be omitted and the movement of the portions 10 of the members 9, under the influence of centrifugal force, will be found sufficient to clamp and hold the buckets in place.

I claim:

1. In combination in a turbine wheel, a main wheel member, said member having an enlarged bead at its periphery, a plurality of buckets positioned on said wheel, said buckets provided with parts embracing said bead, and a plurality of holding members positioned one on each side of said wheel member, said holding members provided with inwardly extending parts, adapted, 70 under the influence of centrifugal force, to grip

tional gripping members positioned between said wheel member and said holding members and shaped to contact said bucket members adjacent their ends, said additional members shaped, under the influence of centrifugal force, to exert an increasing pressure upon said bucket members at their ends.

DAVID P. EASTMAN.
